UNITED STATES PATENT OFFICE.

DANIEL M. REYNOLDS, OF CHICAGO, ILLINOIS.

IMPROVEMENT IN TOY-BEDSTEADS.

Specification forming part of Letters Patent No. 128,249, dated June 25, 1872.

To all whom it may concern:

Be it known that I, DANIEL M. REYNOLDS, of Chicago, in the county of Cook and State of Illinois, have invented a new and Improved Portable Toy-Bedstead; and I do hereby declare the following to be a full, clear, and exact description thereof, which will enable others skilled in the art to which my invention appertains to make and use the same, reference being had to the accompanying drawing forming part of this specification, in which the figure is a side elevation of a bedstead with my improvement applied thereto.

My invention has for its object to provide improved means of securing the side rails to the posts of a toy-bedstead; and to that end it consists in providing the ends of the rails with dovetailed tenons, which slide into mortises formed in the sides of the posts, upon their inner edges, and are secured in position by buttons upon the sides of the posts, which being turned upon their pivots cover the tenons in the mortises and hold them securely in position.

In the accompanying drawing, A A repre-

sent the posts of a bedstead, and B the rails, provided with dovetailed tenons D. C represents a button in the position which it occupies when inserting the end of the rail into the mortise; and C' represents the same when the tenon is secured within the mortise and said button is turned upon its pivot over the end of the rail, the tenon being shown by dotted lines.

In setting up a bedstead when constructed in accordance with my invention, the rails being brought into position the tenons are slid into the mortises, the buttons turned over the same, making a simple and cheap connection.

Having thus described my invention, what I claim as new, and desire to secure by Letters Patent, is—

Rails B, provided with dovetailed tenons D, in combination with mortised posts A and buttons C C', the whole arranged substantially in the manner and for the purposes described.

DANIEL M. REYNOLDS.
